CLAIM

The ornamental design for an elasticized wrist band containing a bottom cushion, as shown and described.

DESCRIPTION

FIG. 1 is a front and side perspective view of an elasticized wrist band containing a bottom cushion, showing my new design;

FIG. 2 is a front view thereof, the rear view being of identical appearance;

FIG. 3 is a side view thereof, the opposite side view being of identical appearance;

FIG. 4 is a top view thereof; and,

FIG. 5 is a bottom view thereof.

The fragmentary criss-cross pattern shown in the drawing is understood to represent fabric and is repeated uniformly throughout the areas shown.
